US00D839796S

(12) **United States Design Patent** (10) Patent No.: **US D839,796 S**
(45) Date of Patent: **** Feb. 5, 2019**

(54) **BEARER CONTAINER FOR A MULTI-AXIS AIRCRAFT**

(71) Applicant: **Nan-Chang Chiu**, Kaohsiung (TW)

(72) Inventor: **Nan-Chang Chiu**, Kaohsiung (TW)

(**) Term: **15 Years**

(21) Appl. No.: **29/596,228**

(22) Filed: **Mar. 7, 2017**

(51) LOC (11) Cl. **12-16**

(52) U.S. Cl.

USPC **D12/161**; D12/345

(58) **Field of Classification Search**

USPC D12/159-162, 345, 400-401, 415;
D26/88-89

CPC B60G 2204/416; B60G 2204/418

CLAIM

The ornamental design for a bearer container for a multi-axis aircraft, as shown and described.

DESCRIPTION

FIG. 1 is a top, perspective view of a bearer container for a multi-axis aircraft showing my design;

FIG. 2 is a side elevational view thereof;

FIG. 3 is a top plan view thereof;

FIG. 4 is a bottom plan view thereof;

FIG. 5 is a bottom perspective view thereof; and,

FIG. 6 is a cross-sectional view taken along section line 6-6 of FIG. 3.

1 Claim, 6 Drawing Sheets
